UNITED STATES PATENT OFFICE.

HENRY BOOT, OF PHILADELPHIA, PENNSYLVANIA, ASSIGNOR TO THOMAS DOLAN & CO., OF SAME PLACE.

DESIGN FOR NUBIA.

Specification forming part of Design No. 6,776, dated July 22, 1873; application filed June 28, 1873.

A.

To all whom it may concern:

Be it known that I, HENRY BOOT, of Philadelphia, Pennsylvania, have invented a Design for a Nubia, of which the following is a specification:

My design for a nubia is clearly illustrated by the figure in the accompanying drawing, and consists of a stripe or stripes, A, and border B upon a groundwork or body, D, of plain knitted loops.

The stripe A is composed of two zigzag bars adjoining each other at the angles so as to form a row of diamond-shaped figures, the threads of which the said bars are composed being interlocked with those of the body of the nubia, and the whole forming a light open fabric with numerous interstices.

The border B is formed of the same elements

as the stripe A, it having a central row of open diamond-shaped figures, bounded on both sides by one or more zigzag bars, as shown.

Irrespective of the colors employed, I claim—

1. The design for the stripe A, as shown and described.
2. The design for the border B, as described and represented.
3. The design for the whole nubia, including the stripe A, border B, and body D.

In testimony whereof I have signed my name to this specification in the presence of two subscribing witnesses.

HENRY BOOT.

Witnesses:

CLINTON M. LATOURETTE,
LEWIS T. GODFREY.
